UNITED STATES PATENT OFFICE.

WADE H. REICHARD, OF ROCHESTER, NEW YORK, ASSIGNOR TO GENERAL RAILWAY SIGNAL COMPANY, OF ROCHESTER, NEW YORK.

ELECTRICAL INTERLOCKING SYSTEM.

Application filed April 23, 1927. Serial No. 186,048.

This invention relates to railway interlocking systems of the electrically controlled electric power operated type, and more particularly to cross protection means for such systems.

In order to avoid complicating the description of the present invention the term "traffic controlling device" has been used in this specification to designate any one of the various devices used for governing and directing the movement of trains in interlocking systems, such as, power operated signals, switch machines, movable point frogs, derails, etc. In interlocking systems of the usual type, and in the system to which the present invention is shown applied, various traffic controlling devices are interlocked by having the control levers of conflicting routes mechanically interlocked in such a way that a lever cannot be moved to a position to conflict with a route already set up. In interlocking systems of this kind it is necessary to assure that a lever cannot get out of correspondence with the traffic controlling device, and vice versa a traffic controlling device cannot get out of correspondence with the position of the lever, and in this particular system this is accomplished by providing interlocking means on a lever permitting the lever to be moved part way only, this locking means being unlocked in response to the flow of dynamic current as the traffic controlling device has responded to a change in the position of the control lever, upon which the stroke of the lever may be completed. In an interlocking system of this kind, as well as in systems of other kinds, it is of course necessary to provide means which guards against the response of a traffic controlling device to current applied thereto through an unauthorized path, and in accordance with the present invention it is proposed to provide cross protection means which will guard against unauthorized operation of the traffic controlling device. This cross protection means is constructed so as not to respond to either the operating current flowing in response to movement of the lever, or respond to dynamic indication current flowing after the traffic controlling device has been moved in response to a change in its control lever, but which will respond if unauthorized current flows which has been applied to the control circuit at a point beyond the control lever contacts.

More specifically this cross protection device comprises a snap or stick circuit interrupter, including two coils contained on magnetic cores arranged in multiple with each other and in series with a soft iron armature, one core of which has an air gap therein, the coil on the core having an air gap being connected in the common return wire of the circuit arrangement and the other coil being connected in the dynamic indication circuit portion thereof, these coils having their turns so arranged that the flow of dynamic indication current sets up a local flux in the two cores in series. Also by reason of the core structure employed, the flow of a limited current in the common return wire coil only will not cause operation of the cross protection device.

Other objects, purposes and characteristic features of the present invention will be apparent from the drawings when taken in connection with the following description.

In describing the invention in detail reference will be made to the accompanying drawings in which:

Fig. 1 illustrates conventionally a layout view of a switch machine having a control circuit embodying the present invention, and forming a part of a novel interlocking system;

Fig. 2 is a side elevation of a cross protection relay embodying the present invention, and conventionally illustrated in Fig. 1, showing portions of the coils thereof cut away;

Fig. 3 is a plan view of the cross protection relay shown in Fig. 2, and

Fig. 4 is a partial sectional view taken on the line 4—4 of Fig. 2 as viewed in the direction of the arrows.

In illustrating the present invention, referring to Fig. 1, a switch machine SM together with its control lever L and a portion of the interlocking mechanism, together with the control circuits involved, has been shown as an illustration of how the present invention may be applied to a traffic controlling device of an interlocking system. The switch machine SM conventionally shown may be an electrically operated switch machine of any suitable construction, but preferably comprises a switch machine such as shown in the prior patent to Howe No. 1,466,903 dated Sept. 4, 1923; and the lever L is one of the type more specifically described in the

patent to Howe No. 1,163,154 dated Dec. 7, 1915. Before going into the interlocking circuit arrangement embodying the present invention and shown in Fig. 1 it is deemed expedient to consider the specific construction of one form of cross protection relay CR embodying the present invention conventionally shown in Fig. 1 and more specifically shown in Figs. 2, 3 and 4.

Referring to Fig. 2 the cross protection relay CR preferably comprises a core structure comprising yokes 1 and 2 mechanically fastened together and spaced apart by cores 3 and 4, of which the core 4 has an air gap which is maintained fixed by a washer or bushing 5 made of suitable non-magnetic material, such as brass or fibre. The core 3 is fastened to the yoke 2 by a tapered head machine screw 6 and to the yoke 1 by means of a small end of the core 3 passing through said yoke 1 and being riveted over as shown at 6¹ and the core 4 is held in place by the tapered head machine screw 7 constructed of non-magnetic material, such as brass. This core structure is supported on a suitable panel or wall of non-magnetic material such as the panel 10 shown by a bolt 11, the core structure being maintained in its proper vertical position by the dowel pin 12. On the cores 3 and 4 are contained coils 13 and 14, the preferred constants of which will be given hereinafter.

The yoke 2 extends a considerable distance beyond the coil 14 and supports a vertically disposed base member 16, fastened thereto by screws 16¹, and having pivotally mounted thereon near its upper end a reset lever 17, the two depending ears of which are pivotally supported by screws 17^b (see Fig. 4). This yoke 2 is also provided with an anvil 18 on which is pivoted the end of the armature 19, which armature is constructed of suitable soft iron. The armature 19 is maintained in cooperative relation with the anvil 18 by a flat headed screw 20, which although not in engagement with the yoke 2 prevents the armature 19 from getting out of cooperation with the anvil 18. Near the extreme upper end of the armature 19 is provided with a residual pin comprising a non-magnetic rivet 21, this rivet engages the yoke 1 of the core structure when the armature 19 is attracted and is provided to avoid this armature being held in its attracted position by residual magnetism.

The end of the armature 19 is provided with a slot 24, and a thin leaf spring 19^a is fastened near the lower end of this armature 19, as by screw 19^b, having its hooked end engaging this slot. The finger 23 has its rear end converging as shown at 23^a (Fig. 4), which converging part lies on the curved upper end of the leaf spring 19^a. The upper end of the base member 16 is shaped to constitute an anvil similar to the anvil 18, and the finger 23 has its other end slotted and bent to form a

transverse groove resting on said anvil, the finger 23 being held in its seated position by a screw 23^b. The finger 23 carries two contacts 25 and 25^a (see Fig. 4), which are insulated from the finger 23, but are electrically connected together by a conducting strap 27. These contacts are adapted to engage the contacts 28 and 28^a, which are also made of suitable non-oxidizing conducting material supported on the ends of spring fingers 29 and 29^a (see Fig. 3). The spring fingers 29 and 29^a are supported by and electrically connected to binding posts 31 and 31^a on an insulating slab 33 fastened to the yoke 1 by screws 34 (see Fig. 3). From this it readily appears that a circuit leading to and away from binding posts 31 and 31^a will be closed if the finger 23 is in its raised position and is held there by the armature 19 in its retracted position. Also, that upon attraction of the armature 19 this armature moves freely for the distance of the slot 24, after which the upstanding lip of the armature engages the hooked end of the spring 19^a and causes this spring to be moved with the armature 19 and finally disengages the finger 23 and causes this finger to drop and the contacts 25, 25^a, 28 and 28^a to interrupt the circuit.

The reset lever 17 heretofore mentioned has a narrow downwardly projecting part 17^a (see Fig. 4) which projects through an opening in the finger 23. The lower offset portion of this arm 17^a is shaped to be engaged by the underside of the finger 23 when the finger 23 is in its lower circuit breaking position (shown by dotted lines), a spring 36 being provided for maintaining the reset lever in its normal position. A block of insulating material 37 is screw fastened to the lever 17 for the purpose of lifting the spring fingers 29 and 29^a when the lever 17 is depressed for the purpose of reclosing the contacts 25, 25^a, 28 and 28^a, these contacts however not being closed unless the lever has first been depressed to bring the finger 23 to its raised latched position and then has been returned to normal to permit the contacts 28 and 28^a to get into contacting relation with contact 25 and 25^a. In order to restore the armature 19 to its normal position, in which it has been shown, upon depression of the reset lever 17, and in order to avoid the armature being attracted unless a magnetic pull of a predetermined extent exists, a spring 40 fastened between one end of the Z-shaped retainer 41 and the armature 19 is provided. The tension of this spring 40 may be varied at will by turning the threaded screw 42 locked by a nut 43 which determines the position of the retainer 41 and in turn the tension of this spring. The normal position of the armature 19 is determined by the adjustable stop bolt 44 which may be locked in position by the lock nut 45, so that not only may the tension by which the armature 19 is held in its normal position be

adjusted but also the air gap through which the fluxes for operating this armature 19 must pass, may be adjusted.

On the insulating slab 33 are mounted another pair of terminal or binding posts 47 and 47^a which support two spring contact fingers 49 and 50 respectively (see Figs. 2 and 3). The spring contact 50 is somewhat longer than the spring contact 49 so as to enable it to be lifted by the insulating block 51 fastened to the end of a pin 52 slidably mounted in the insulating slab 33. This pin 52 is of such length that the normally separated spring fingers 49 and 50 are brought into contacting relationship when the armature 19 is attracted into its dotted position and the finger 23 assumes its dotted position, the dropping of the pin 52 being limited by the insulating block 52 striking the insulating slab 33.

From this construction it readily appears that attraction of the armature 19 interrupts a circuit leading to and from the binding posts 31 and 31^a but completes a circuit leading through the binding posts 47 and 47^a. Also, it readily appears that the circuit leading to and from the binding posts 31 and 31^a cannot be forcibly held closed by the lever 17, because the insulating block 37 will not allow this circuit to be closed until the reset lever 17 is returned to its normal position.

Referring to Fig. 2 it readily appears that if current of a limited extent only is flowing in the coil 14 that the flux produced by such current is shunted away from the armature 19 by the core 3, and further it is apparent that if currents of a limited extent flow in the two coils 13 and 14 in such a direction that the magneto-motive-force in one core is directed upward and the magneto-motive force in the other coil is directed downward that a local magnetic flux will be set up in these cores which will not materially affect the armature 19.

In order to get a clear understanding of the operation of the cross protection relay just described when used in a novel way in the circuit for the switch machine shown in Fig. 1 of the drawings, it is deemed expedient to consider the operation of the switch machine and then consider the application of unauthorized current to certain portions of the circuit arrangement shown in Fig. 1.

The interlocking system shown in Fig. 1 includes a plurality of levers, of which the lever L only has been shown. The levers of conflicting traffic controlling devices are mechanically interlocked by the usual interlocking mechanism, of which the tappet bar 54 moved by the roller 55 operating in the slot 56 of the lever L, only has been shown. Let us assume that the operator desires to operate the switch S from the normal straight track position in which traffic may move over the main track MT to a position to permit

traffic to move into the siding. In order to do so the operator will pull the lever L until the contact blocks 57 and 58 assume the half reverse position as indicated by the letters HR, the operator being prevented from moving the lever L beyond this position by reason of the latch bar 59. With the lever L assuming the half reverse position a circuit which may be traced as follows is completed:—beginning at the battery B, wire 60, coils of the safety magnet SI, wire 61, contacts 58—62, wire 63, reverse wire RW, contacts 64—65, wires 66 and 67, armature of the motor M, wires 68 and 69, contacts 70—71, wire 72 field winding 73 of the motor M, wire 74, common return wire C, coil 14 of the cross protection relay CR, wire 75, contacts 25—28, wire 76 back to the battery B.

The completion of this circuit causes movement of the switch S to the siding position by operation of the switch machine SM. The flow of this operating current in this circuit will not cause operation of the cross protection relay CR, because the flux due to the current flowing in the coil 14 is magnetically shunted away from the armature 19 by the heavy core 3, so that very little, if any, of the flux passes through the armature 19.

Just before the operating stroke of the switch machine SM is completed the pole changer contacts 64 and 70 are moved to their dotted position, which places the relation of the field and armature of the motor M in condition for returning the switch back to its normal position upon return of the lever. Also, this reversal of polarity of the armature with respect to the field of the motor M causes a dynamic indication and snubbing current to flow in the following circuit:—beginning at the armature of the motor M wire 67, contacts 70—80, wire 81, field winding 73 of the motor M, wire 74, common return wire C, coil 14 of the cross protection relay CR, wire 92, coil 13 of the cross protection relay CR, wire 82, coils of the indication magnet IM, wire 83, contacts 57—84 of the lever L, wire 85, normal wire NW, contacts 64—86, wire 68 back to the armature of the motor M.

The flow of this dynamic indication current causes the armature of the indication magnet IM to be attracted, thus effecting operation of the latch 88 which operates the latch bar 59, thereby unlocking the lever to permit the operator to complete the stroke of this lever, which stroke if completed unlocks certain conflicting levers. The flow of current in this dynamic indication circuit not only dynamically unlocks the lever when the switch machine has responded to a change in the position of the lever, but also checks the integrity of the circuit including the coil 13 of the cross protection relay CR, for if this circuit should be open at any point no indication can be received and the interlock-

ing system is tied up entirely until the trouble has been found and rectified. The flow of the current in the dynamic indication circuit just traced also snubs or brakes the motor after having completed its operating stroke. This flow of dynamic indication current will not operate the cross protection relay CR, because the magneto-motive forces set up in the two coils 13 and 14 of this device are in a direction as indicated by the solid arrows and therefore cause the flow of flux in a local magnetic circuit not including the armature 19.

When the operator desires to return the switch S to its normal main track position he will push the lever L, providing this lever is not locked by the interlocked mechanism, to the half normal position as indicated by the letter HN. With the switch machine still in the take siding position an operating circuit is completed which is very analogous to the operating circuit heretofore traced, and for this reason it is deemed unnecessary to specifically trace and consider this normal operating circuit.

Let us now assume that the apparatus of Fig. 1 is in its normal condition, as shown, and that current from the upper or positive side of the battery B is applied to the reverse wire RW, through some unauthorized connection such as a ground, a cross or the like. An unauthorized circuit such as just mentioned will cause the flow of current through two paths in multiple as follows:—(1) beginning at the wire RW, contacts 64—65, wires 66 and 67, armature of the motor M, wires 68 and 69, contacts 70—71, wire 72, field winding 73, wire 74, common return wire C, coil 14 of the cross protection relay CR, wire 75, contacts 25—28, wire 76 to the negative side of the battery B, and (2) beginning at the wire RW contacts 57—90, wires 91 and 83, coils of the indication magnet IM, wire 82, coil 13 of the cross protection relay CR, wires 92 and 45 75, contacts 25—28, wire 76 back to the battery B.

The flow of currents in these two circuits in multiple just traced causes magneto-motive-forces to be induced in the coils 13 and 50 14 of the cross protection relay CR in a direction as indicated by the dotted arrows, so that they will cumulatively produce a flux in the armature 19, thereby causing the armature to be attracted and the contacts 25—28 55 to be opened. In practice the plant maintainer will be called out to locate and rectify the trouble caused by an unauthorized circuit such as just mentioned, the operator's attention being called to the fact that the cross protection relay has been operated by the 60 ringing of the bell BL. The circuit for this bell BL includes contacts 49—50 associated with the cross protection relay CR and terminals B and C of a suitable battery, and is readily traced in the drawings. Another

function of the cross protection relay CR is to cut off the battery if either the wire 61 or any of the wires connected thereto should become grounded. If any of the wires just mentioned should become grounded to the 70 common return wire C current would flow as follows:—from the battery B, wire 60, coils of the safety magnet SI, wires 61 or the wires connected thereto, through an unauthorized path to common return wire C, coil 14, wire 75, contacts 25—28, wire 76, to the battery B. The current flowing in this path would not operate the armature 19 unless the current is fairly large as would ordinarily be the case.

The cross protection relay CR will also be 80 actuated if a cross should occur between the normal and reverse wires NW and RW. With a cross existing between the wires NW and RW current will flow in two paths as follows:—beginning at the battery B, wire 85 60, coils of the safety magnet SI, wire 61, contacts 58—94, wire NW, through the unauthorized connection to the wire RW, from which the circuit will branch out into the two following branches (1) wire RW, contacts 57—90, wires 91 and 83, coils of the 90 indication IM, wire 82, coil 13 of the cross protection relay CR, wires 92 and 75, contacts 25—28, wire 76 to the battery B, and (2) wire RW, contacts 64—65, wires 66 and 67, armature of the motor M, wires 68 and 69, contact 70—71, wire 72, field winding 73 of the motor M, wire 74, common return wire C, winding 14 of the cross protection relay CR, wire 75, contacts 25—28, wire 76 back 100 to the battery B. It will be noted that the flow of currents in the two coils 13 and 14 of the cross protection relay CR are in a direction to produce fluxes which cumulatively act upon the armature 19, so that this armature 19 will be operated. If in the case just considered practically all of the current flow is over the circuit portion including the indication magnet and the coil 13, the armature 19 will still be operated, by reason of the fact 110 that the air gap in the core 4 of the cross protection relay CR prevents this core from shunting the armature 19. Obviously the system described is checked against open circuits in the coils 13 and 14; for if coil 13 115 should become open no indication can be received and if coil 14 should become open the switch machine cannot be operated. Similarly, the system is checked against short circuits in these coils 13 and 14. For instance, 120 at the time a dynamic indication is received the dynamic indication current flows through the coils 13 and 14 in series and under this condition the current flowing in the coil 14 acts to draw or suck at least part of the flux 125 produced in the coil 13 around the armature 19, so that the armature 19 is not attracted. Consequently if the coil 14 should become short circuited this action would not take place and the device CR would be actuated. 130

Similarly if either of the coils 13 or 14 were short circuited, the flow of dynamic indication current would attract the armature 19 and actuate the relay CR, because the shorted 5 coil would act as a choke coil to the upbuilding of a unidirectional flux therein. In like manner the accidental shorting of coil 13 will cause it to act as a choke coil and will cause the armature 19 to be attracted when 10 current is applied to the motor of the switch machine even though under this condition the circuit of the indication magnet including this coil is open at the lever contact.

In practice the number of turns on the 15 coils 13 and 14 must be chosen so as to cause this cross protection relay to function properly under all conditions, and the ratio of turns in these two coils for proper functioning depends on the air gap in the core 4, the 20 cross section of the core 3, the air gap of the armature and the magnetic qualities of the iron used in the various parts of the magnetic structure. In one design of cross protection relay having a magnetic structure as illustrated in Fig. 2 the number of turns for the 25 coil 13 is 304 and the number of turns in the coil 14 is 124, and this cross protection relay functions satisfactorily under all the conditions considered above, and in addition to 30 taking care of the various crosses and grounds heretofore mentioned it also actuates and opens the circuit when the current used by the traffic controlling device is excessive due to jammed parts, a sudden reversal of the motor or motor trouble.

One of the outstanding characteristic features of the present invention is that the cross protection relay embodying the present invention does not require the current flow to 40 be of a particular polarity since the device in itself is not a polarized device, and for this reason it may be used with traffic control devices of various construction. For instance, if the pole changer switch of the switch machine SM were connected to reverse the field of the motor M, instead of the armature as is the case in the wiring diagram shown, the indication current would flow in the opposite direction in the dynamic indication circuit 45 from that of the current flow traced heretofore, and the cross protection relay CR would still function in exactly the same manner as it does with the switch machine shown in which the armature is reversed upon the completion of its stroke; in other words, the cross protection relay embodying the present invention takes cognizance of the direction of flow of current in several parts of a circuit, or in a single part of a circuit in some instances, without being affected by the direction of current flow in the circuit as a whole.

Having thus shown and described one specific design of cross protection relay embodying the present invention, and having shown 60 it applied to a single circuit arrangement,

it is desired to be understood that this has been done for the purpose of showing how the invention may be applied rather than illustrating its scope or the exact construction preferably employed in practice; and that the specific construction shown is susceptible to considerable modifications to adapt the invention to the particular interlocking system or particular traffic controlling device to which the invention is to be applied, all without departing from the scope of the invention or the idea of means underlying the same. 70

What I desire to secure by Letters Patent is:—

1. In an interlocking system, the combination with an electric power operated traffic controlling device including a motor; a source of electrical energy for operating said device; a control circuit for said device including a control wire, a return wire, said 80 motor and said source of current; and an electro-responsive cross protection relay which if actuated disconnects said source of energy from said control circuit; said cross protection relay including a magnetic circuit having two cores connected in multiple which in turn are connected in series with a soft iron armature, one of said cores having an air gap therein; a coil on each of said cores; the coil on the core having an air gap 85 therein being connected in series with said common return wire and the coil on the other core being contained in a dynamic indication circuit completed when traffic controlling device has completed its movement in 90 response to operation of said lever; the coils being so connected that when dynamic indication current flows local magnetic flux not linking said armatures is set up and said armature is not opened, but if current supplied from an unauthorized source is applied to 95 said motor the currents in said coils will produce magneto-motive-forces to cause a resulting flux to pass through the armature and cause operation thereof.

2. In an interlocking system; the combination with an electric power operated traffic controlling device of the type wherein completion of the operating circuit therefore,

which includes a source of energy and a common return wire, causes operation of the motor of said traffic controlling device, and wherein when the operating stroke of said device has been completed a dynamic indication circuit including said common return wire is completed; of a cross protection relay comprising, a magnetic circuit including two cores in multiple one of which has an air gap therein and an armature arranged in series with said multiple cores, a coil on the core having an air gap therein connected in said return wire, a coil on the other core connected in the dynamic indication circuit, the relation of the turns of two coils being such that the flow of dynamic indication current pro- 110

115

120

125

130

duces magneto-motive-forces in the cores in multiple which will set up a local circulating flux in these cores, and whereby if current is applied to the motor through an unauthorized circuit the currents flowing in these two coils produces magneto-motive-forces in said cores to cause the fluxes resulting therefrom to cumulatively pass through said armature and effect operation thereof, and means for disconnecting said source of energy upon operation of said armature.

3. In an interlocking system; the combination with an electric power operated traffic controlling device of the type wherein completion of the operating circuit therefore, which includes a source of energy and a common return wire, causes operation of the motor of said traffic controlling device, and wherein when the operating stroke of said device has been completed a dynamic indication circuit including said common return wire is completed; of a cross protection relay having a magnetic circuit including a core of magnetic material having an air gap therein and a movable armature arranged in series, a coil on said core connected in said common return wire, contacts for disconnecting said source of energy opened when said armature is attracted, a shunting core of magnetic material for magnetically shunting said first mentioned core, and a coil on said shunting core connected in said dynamic indication circuit, the connections of said coils being such that a local flux not linking said armature is set up in the two cores when a dynamic indication current flows, and the number of turns in the first mentioned coil, the length of the air gap and the cross section of the cores being so chosen that operating current of normal value flowing in the common return wire will not actuate said armature to open said contacts.

4. In an interlocking system; the combination with an electric power operated traffic controlling device of the type wherein completion of the operating circuit therefore, which includes a source of energy and a common return wire, causes operation of the motor of said traffic controlling device, and wherein when the operating stroke of said device has been completed a dynamic indication circuit including said common return wire is completed; of a cross protection relay having a magnetic circuit including a core of magnetic material having an air gap and a movable armature arranged in series, a coil on said core connected in said common return wire, contacts for disconnecting said source of energy opened when said armature is attracted, a shunting core of magnetic material for magnetically shunting said first mentioned core, and a coil on said shunting core connected in said dynamic indication circuit, the connections of said coils and the ratio of turns thereof being such that

a local flux not linking said armature is set up in the two cores when a dynamic indication current flows, and the number of turns in the first mentioned coil, the length of the air gap and the cross section of the cores being so chosen that operating current of normal value flowing in the common return wire will not actuate said armature to open said contacts, but if the operating current is excessive said armature will be operated to cut off said source of current by opening said contacts.

5. In an interlocking system, the combination with an electric power operated traffic controlling device wherein completion of the operating circuit therefore, which includes a source of energy and a common return wire, causes operation of the motor of said traffic controlling device, and wherein when the operating stroke of said device has been completed a dynamic indication circuit including said common return wire is completed; a cross protection relay having a magnetic circuit including a core of magnetic material having an air gap and a movable armature arranged in series, a coil on said core connected in said common return wire, contacts for disconnecting said source of energy opened when said armature is attracted, a shunting core of magnetic material for magnetically shunting said first mentioned core, and a coil on said shunting core connected in said dynamic indication circuit, the connections of said coils being such that a local flux not linking said armature is set up in the two cores when a dynamic indication current flows, and the number of turns in the first mentioned coil, the length of the air gap and the cross section of the cores being so chosen that operating current of normal value flowing in the common return wire will not actuate said armature to open said contacts, but if the operating current is excessive said armature will be operated to cut off said source of current by opening said contacts.

6. A cross protection relay comprising; two cores connected in multiple one of which has an air gap therein; an armature connected in series with the two multiple cores; a contact operated by said armature; a coil on each of said cores; the cross-sections of the cores, the length of the air gap and the number of turns in the coils, being so selected that the armature is not attracted if a certain current flows in the coil on the core having an air gap but is attracted if this same current flows in both of the coils and flows in a direction therein so that the magneto-motive-forces act cumulatively upon said armature.

7. A cross protection relay comprising; two cores connected in multiple one of which has an air gap therein; an armature connected in series with the two multiple cores; normally closed contacts tending to assume an open position carried by pivoted means latched in the normal position by said armature, a coil on each of said cores; the cross-sections of the cores, the length of the air gap and the number of turns in the coils, being so selected that the armature is not attracted if a certain current flows in the coil on the core having an air gap but is attracted if this same current flows in both of the coils and flows in a direction therein so that the magneto-motive-forces act cumulatively upon said armature.

8. A cross protection relay comprising, an armature, a winding associated with said armature which if energized attracts said armature, a latch movable substantially about the pivot about which said armature moves and having a limited distance of movement relatively to said armature, contacts tending to assume an open position held closed by said latch, the distances of relative movement between said armature and latch and the distances of movement of the armature being so selected that upon attraction of the armature it will be free to move for said limited distances after which it will carry with it said latch, whereby the inertia of the armature is used to trip said latch.

9. In an interlocking system; the combina-

tion with an electric power operated traffic controlling device of the type wherein completion of the operating circuit therefore, which includes a source of energy and a common return wire, causes operation of the motor of said traffic controlling device, and wherein when the operating stroke of said device has been completed a dynamic indication circuit including said common return wire is completed; of a cross protection relay comprising, a magnetic circuit including two cores in multiple one of which has an air gap therein and an armature arranged in series with said multiple cores, a coil on the core having an air gap therein connected in said return wire, a coil on the other core connected in the dynamic indication circuit, the relation of the turns of two coils being such that the flow of dynamic indication current produces magneto-motive-forces in the cores in multiple which will set up a local circulating flux in these cores, and whereby if current is applied to the motor through an unauthorized circuit the currents flowing in these two coils produces magneto-motive-forces in said cores to cause the fluxes resulting therefrom to cumulatively pass through said armature and effect operation thereof, means for disconnecting said source of energy upon operation of said armature, and means for sounding an alarm upon operation of said armature.

In testimony whereof I affix my signature.

WADE H. REICHARD.
